HYDRAULIC CONTROL SYSTEM

Howard F. Lawrence, Philadelphia, Pa., assignor
to American Engineering Company, Philadelphia, Pa., a corporation of Pennsylvania

Original application March 24, 1937, Serial No.
132,689, now Patent No. 2,221,313, dated No-
vember 12, 1940. Divided and this application
May 29, 1940, Serial No. 337,803

8 Claims. (Cl. 60—52)

This application is a division of my pending application Ser. No. 132,689, filed March 24, 1937, on which Patent No. 2,221,313 was granted on November 12, 1940, for Hydraulic control systems, and the invention herein described relates to hydraulic control systems, and more particularly to systems employed to reverse the direction of discharge of pumps when the pressure developed thereby exceeds a predetermined value.

One object of the present invention is to provide a generally improved and simplified control system of the stated character which is fully automatic in operation.

Another object is to provide a system of the stated character wherein the pump controls are positively actuated to effect a reversal of the discharge thereof.

A further and more specific object is to provide in a fluid system including a high pressure pump for actuating feeding rams, a control device which automatically and positively effects reversal of the discharge of the pump when the rams reach their limit of travel in either direction.

Other and further objects will become apparent as the description of the invention progresses.

Of the drawing:

Fig. 1 is a plan view, partly in section and diagrammatic in part, showing the general assembly of the hydraulic control system comprising the present invention.

Fig. 2 is a sectional view taken substantially along line 2—2 of Fig. 1.

Referring to the drawing, the hydraulic control system comprising the present invention includes a pump 140 which, in the present instance, is adapted to operate a pair of fluid motors 156. The operation of said fluid motors is controlled by a valve 141, which in turn is actuated by a control system hereinafter fully described.

Pump 140 in the present instance is operated by an electric motor 142 through any suitable coupling 143. Fluid is supplied to the system from a makeup or supply tank 144 which is connected to one side of the pump by an intake pipe 145. Pump 140 may be of the general type shown in Patent No. 1,077,979, or any other suitable type and, as shown in Fig. 1, discharges fluid under pressure into a pipe 146, which pipe is connected to a port 147 communicating with the central cylindrical chamber 148 of valve 141. Valve 141 has provided therein a pair of spaced

ports 149 and 150, which ports are connected respectively to one end of pipes 151 and 152. Pipes 151 and 152 are connected by branch pipes 153 and 154, to the opposite ends of the cylinders 155 of fluid motors 156. Cylinders 155 have pistons 157 operating therein to which feeding rams may be connected in any suitable manner. Valve 141 has also provided therein a port 158 at one end thereof which is connected to makeup tank 144 by means of a pipe 159. The reduced portions 160 and 161 at the opposite ends of chamber 148 are connected by means of a pipe 162. Valve 141 has provided therein a valve element 163 having a pair of valve heads 164 and 165 connected by reduced portion 166. Valve element 163 has a stem 167 secured thereto which extends through the end wall 168 of valve 141. The opposite end of valve stem 167 has secured thereto a piston 169 which operates in the cylinder 170 of a fluid motor 171 secured in any suitable manner, such as by bolts 172, to the casting of valve 141. The head end 173 of motor 171 is connected to a normally closed port 174 of a control valve 175 by means of a pipe 176. The other end of motor 171 is connected to a second port 177 of control valve 175 by means of a second pipe 178. Control valve 175 has provided therein a pair of cylindrical chambers 179 and 180 which are connected at one end thereof by a passage 181 and ports 182 and 183. Chamber 179 has provided therein a valve element 184 consisting of a pair of valve heads 185 and 186 connected by a reduced portion 187. The upper end of valve element 184 has secured thereto a reduced guiding extension 188 which extends through a guiding aperture 189 provided at the upper end of control valve 175. Chamber 180 also has provided therein a similarly constructed valve element 190 consisting of a pair of valve heads 191 and 192 connected by a reduced portion 193. One end of valve 190 also has secured thereto a reduced guiding extension 194 which extends through a second guiding aperture 195 in line with chamber 180. The upper end of chamber 179 is connected to pipe 152 by means of a pipe 196. The upper end of chamber 180 is connected to pipe 151 by a pipe 197. Passage 181 is connected to a small pump 198 by means of a pipe 199. Pump 198 is connected to the shaft 200 of pump 140 by a chain and sprocket mechanism 201. Fluid is drawn into pump 198 from makeup tank 144 through a pipe 202. Pipe 199 has provided therein an adjustable relief valve 203 which in turn is connected to makeup tank 144 by means of a pipe 204. Relief valve 203 may be

of any suitable construction which will open to exhaust when the pressure imposed thereon exceeds a predetermined value, as fully set forth in my above noted Patent No. 2,221,313.

The cylindrical chambers 179 and 180 of control valve 175 are interconnected intermediate the ends thereof by means of a transverse passage 205. A second passage 206, extending substantially at right angles to passage 205, extends from the latter to the outside of the casing of valve 175, and a pipe 207 connects passage 206 with makeup tank 144. Any fluid leaking past the upper guide portions 188 and 194 of valve members 184 and 190 respectively, flows into a vertical passage 208 which extends from the upper end of valve 175 to passage 206. It will be observed that when valve members 184 and 190 are in their uppermost position, the ports 177 and 174 are only partially covered by the valve heads 185 and 191 respectively. Thus, when valve 190 is in the position shown in Fig. 1, and fluid from pipe 151 flows through pipe 197, port 174 and pipe 176 to the head end of piston 169, the fluid at the other end of cylinder 170 will pass through pipe 178, port 177, the annular chamber between valve heads 185 and 186, transverse passage 205, passage 206, and pipe 207, to makeup tank 144. On the other hand, when valve 190 is in its upper position, and valve 184 is in its lower position, fluid from the head end of cylinder 170 will flow to makeup tank 144 through pipe 176, port 174, the chamber between valve heads 191 and 192, transverse passage 205, passage 206, and pipe 207.

From the foregoing description it is seen that port 147 of valve 141 at all times is disposed between valve heads 164 and 165. When the parts are in the position shown in Fig. 1 fluid from pump 140 enters the central chamber 148 of valve 141 through pipe 146 and port 147. Fluid then flows to the right hand ends of cylinders 155 through pipe 151, causing pistons 157 to move to the left. Fluid at the left hand end of cylinders 155 then flows to makeup tank through pipes 154, 152, port 150, chamber 148, the reduced portion 161 thereof, and pipe 159. When pistons 157 reach the limit of their travel in this direction, pressure builds up in pump 140. This pressure is transmitted to the upper end of valve member 190 through pipe 197. When this pressure is sufficient to overcome that imposed against the lower end of said valve member by the small pump 198, valve element 190 moves downwardly, thereby uncovering port 174 to permit fluid under pressure to enter the head end of motor 170. Piston 169 of motor 171 now actuates valve element 166 to its other extreme position of adjustment, and thereby establishes communication between pump 140 and pipe 152. Fluid now enters the left hand end of cylinders 155, thereby causing the pistons 157 operating therein to move to the right. The fluid at the right hand end of cylinders 155 will now flow back to makeup tank through pipes 153, 151, port 149, chamber 148, reduced portion 160, pipe 162, reduced portion 161, and pipe 159. As soon as valve 163 moves downwardly to connect ports 147 and 150, thereby causing the discharge of pump 140 to enter pipe 152, the pressure at the upper end of valve head 191 is relieved, and consequently valve 190 is moved upwardly by the pressure from pump 198. The fluid at the upper end of chamber 180 now passes to makeup tank through pipes 197 and 151, port 149, chamber 148, pipe 162, port 158 and pipe 159. When pis-

tons 157 reach the limit of their travel in this direction, the pressure developed by pump 140 again builds up. Pipe 152, it will be remembered, is connected to the upper end of chamber 179 by means of pipe 196, and when this pressure exceeds that imposed upon the lower end of valve member 184 by small pump 198, said valve element will move downwardly to uncover port 177. When this occurs, fluid will enter the piston rod end of motor 171 through port 177 and pipe 178, causing piston 169 to actuate valve element 163 to the position shown in Fig. 1. Fluid from pump 140 will now again enter the right hand ends of cylinders 155, causing the pistons 157 operating therein to move to the left. The fluid at the left hand end of cylinders 155 now flows to makeup tank as previously described, through pipes 154, 152, port 150, chamber 148, and pipe 159. As soon as valve 163 is shifted to the position shown in Fig. 1, the pressure of the fluid at the upper end of chamber 179 is relieved, causing pump 198 to move valve element 184 upwardly. Fluid at the upper end of chamber 179 will now flow to makeup tank through pipe 106, pipe 152, chamber 148 of valve 141, and pipe 159. This procedure is repeated to effect reverse operations of pistons 157 when they reach their limit of travel in either direction.

It therefore is seen that a simplified, as well as highly improved hydraulic control system has been provided which positively reverses the discharge of the pump when the pressure in the system exceeds a predetermined value.

While the embodiment herein shown and described is admirably adapted to fulfill the objects primarily stated, it is to be understood that the invention is not to be limited thereto, since it may be embodied in other forms, all coming within the scope of the claims which follow.

What is claimed is:

1. In a device of the class described, the combination of a pump, a pair of pipes for alternately delivering fluid pressure from said pump, a distributing valve for controlling the flow of fluid in said pipes, normally inoperative fluid pressure means for adjusting said valve to different positions of adjustment, valve means for controlling the operation of said fluid pressure means, means connecting one end of said valve means to the pressure side of said pump, an auxiliary source of fluid pressure, and means connecting the other end of said valve means to said auxiliary source of pressure, whereby when the pressure imposed upon said valve means by said pump exceeds that imposed thereon by said auxiliary source of fluid pressure said valve means operates to render said fluid pressure means operative to effect adjustment of said distributing valve.

2. In a device of the class described, the combination of a pump, a pair of pipes for alternately delivering fluid pressure from said pump, a distributing valve for controlling the flow of fluid in said pipes, normally inoperative fluid pressure means for adjusting said valve, a valve mechanism consisting of a pair of valve elements for controlling the operation of said fluid pressure means, said valve mechanism including a pair of discharge ports normally disconnected from the pressure in said pipes by said valve elements, fluid conducting means connecting said discharge ports to said fluid pressure means, means connecting one end of one of said valve elements with one of said pipes, means connecting one end of the other of said elements with the other of said pipes, an auxiliary source of

fluid pressure, means connecting the other end of each of said valve elements to said auxiliary source of pressure, whereby when the pressure in either of said pipes imposed upon said valve elements exceeds that imposed upon said valve elements by said auxiliary source of fluid pressure the valve element subjected to such pressure moves to open the associated discharge port to pressure, thereby causing adjustment of said distributing valve by said fluid pressure means.

3. In a device of the class described, the combination of a pump, a pair of pipes for alternately delivering fluid pressure from said pump, a distributing valve for controlling the flow of fluid in said pipes, normally inoperative servo motor means operated by the fluid pressure developed in said pump for actuating said distributing valve to different positions of adjustment, a valve mechanism comprising a pair of valve elements for controlling the operation of said servo motor means, means connecting one end of one of said valve elements to one of said pipes, means connecting one end of the other of said valve elements to the other of said pipes, an auxiliary pump, and means connecting the opposite end of each of said valve elements to said auxiliary pump, whereby when the pressure developed by said first mentioned pump exceeds that developed by said auxiliary pump, the valve element subjected to such pressure operates to render said servo motor operative to effect adjustment of said distributing valve.

4. In a device of the class described, the combination of a pump, a pair of pipes for alternately delivering fluid pressure from said pump, a distributing valve for controlling the flow of fluid in said pipes, normally inoperative servo motor means operated by the fluid pressure developed in said pump for actuating said distributing valve to different positions of adjustment, a valve mechanism comprising a pair of valve elements for controlling the operation of said servo motor means, means connecting one end of one of said valve elements to one of said pipes, means connecting one end of the other of said valve elements to the other of said pipes, an auxiliary pump, means connecting the opposite end of each of said valve elements to said auxiliary pump, whereby when the pressure developed by said first mentioned pump exceeds that developed by said auxiliary pump, the valve element subjected to such pressure operates to render said servo motor operative to effect adjustment of said distributing valve, and means for varying the pressure developed by said auxiliary pump.

5. In a device of the class described, the combination of a main pump, a double-acting fluid motor operated by the said main pump, means controlling the flow of fluid from said pump to said fluid motor, normally inoperative servo motor means for actuating said controlling means, valve means for controlling the operation of said servo motor, means connecting one end of said valve means to the pressure side of said main pump, an auxiliary pump, and means connecting

the other end of said valve means to the pressure side of said auxiliary pump whereby when the pressure imposed upon said valve means by said main pump exceeds that imposed thereon by said auxiliary pump, said valve means operates to render said servo means operative to effect adjustment of said controlling means.

6. In a device of the class described, the combination of a main pump, a fluid motor operated by said main pump, a distributing valve for controlling the flow of fluid from said pump to said fluid motor, normally inoperative means for adjusting said distributing valve, valve means for controlling the operation of said normally inoperative means, means connecting one end of said valve means to the pressure side of said main pump, an auxiliary pump, and means connecting the other end of said valve means to the pressure side of said auxiliary pump whereby when the pressure imposed upon said valve means by said main pump exceeds that imposed thereon by said auxiliary pump said valve means operates to render said normally inoperative means operative to effect adjustment of said distributing valve.

7. In a device of the class described, the combination of a main pump, a fluid motor operated by said main pump, a distributing valve for controlling the flow of fluid from said pump to said fluid motor, normally inoperative means for adjusting said distributing valve, valve means for controlling the operation of said normally inoperative means, means connecting one end of said valve means to the pressure side of said main pump, an auxiliary pump, means connecting the other end of said valve means to the pressure side of said auxiliary pump whereby when the pressure imposed upon said valve means by said main pump exceeds that imposed thereon by said auxiliary pump, said valve means operates to render said normally inoperative means operative to effect adjustment of said distributing valve, and means for varying the pressure developed by said auxiliary pump.

8. In a device of the class described, the combination of a main pump, a fluid motor actuated by said pump, a distributing valve for controlling the flow of fluid from said pump to said fluid motor, normally inoperative means for adjusting said distributing valve, a valve mechanism for controlling the operation of said normally inoperative means, said valve mechanism comprising a pair of valve elements, means for alternately connecting one end of each of said valve elements to the pressure side of said main pump, an auxiliary pump, and means connecting the opposite end of each of said valve elements to the pressure side of said auxiliary pump whereby when the pressure imposed upon either of said valve elements by said main pump exceeds that imposed thereon by said auxiliary pump the said valve element subjected to such pressure operates to render said normally inoperative means operative to effect adjustment of said distributing valve.

HOWARD F. LAWRENCE.
